METHOD OF MAKING HOLDERS WITH REPLACEABLE CUTTING BLADES

Miles M. Abbott, Chicago, Ill., assignor to Tenderet Corporation, Chicago, Ill., a corporation of Illinois

Application December 30, 1940, Serial No. 372,287

3 Claims. (Cl. 22—203)

The present invention relates to improvements in a holder having replaceable cutting blades and method of making the same, and it has special reference to an improved method of forming slots in the holder and to the cutting blades to be replaceably attached in the slots of the holder.

One object of the invention is the provision of a holder of this character which is inexpensive to construct, strong and durable, and provided with a cavity of the desired size and shape into which a molten mass of metal is poured to provide a plurality of slots and openings extending transversely of the slots.

Another object is the provision of cutting blades constructed in such manner to snuggly fit slots molded in the holder and with openings at the base of the blades for receiving locking members therethrough to replaceably retain the blades to the holder.

Heretofore, various arrangements of holders and cutting blades have been proposed. In many of such arrangements, the cutting blades are permanently secured as a unit to the holder, and should it be found necessary to replace a blade, the entire holder is removed, and a new one installed. In most instances, the holder and cutting blades are of such construction and arrangement, that it is necessary to ship the same to the manufacturer for repairs. This method is not only costly, but much delay is caused and the device on which the holder is employed, is rendered useless until such repair is made.

As a further aspect of the invention, I provide cutting blades constructed in a manner to be readily and easily removed or inserted in the holder, and whereby each cutting blade may be individually gripped to be removed or inserted.

For a more complete understanding of the invention, reference should now be had to the drawing in which:

Figure 1 is a perspective view of the holder illustrating the cavity therein preparatory to filling the same with a molten mass of metal.

Figure 2 is a perspective view of a plate having strips thereon and attachable to the holder for providing slots and openings in the molten mass of metal poured into the cavity.

Figure 3 is a sectional view illustrating the plate and holder clamped together preparatory to pouring the molten mass of metal into the cavity.

Figure 4 is a perspective view of the holder with the slots and transverse openings cast therein.

Figure 5 is an enlarged detail view in side elevation and partly broken away of one of the cutting blades.

Figure 6 is a perspective view of the holder with the cutting blades locked in position thereon.

Referring more particularly to Fig. 1, my invention is illustrated as applied to a holder having a handle, and of a type employed in meat tendering machines, the cutting blades of which machines are frequently damaged by striking a bone or other substances which may accidentally be placed under the holder.

Further, holders of this character are frequently washed to be cleaned, and when desired, the cutting blades may be readily removed to be sharpened and are easily replaced. The construction being such that by withdrawing a pair of insertable members renders the cutting blades free to be removed, and each end of the cutting blades are provided with notches therein whereby they may be gripped and removed from the holder.

The holder designated as 10 may be of any suitable material and formed, or as shown, may be cast to the required shape, providing a cavity 11 having a relatively flat surface 12 and undercut side edges 13. The top edge 14 of the cavity is machined to provide a smooth flat surface, and is relieved at 15 to form a receiving opening to pour a molten mass of metal into the cavity. The holder 10 is also provided in opposite side edges of the cavity 11 thereof with aligned openings 16—16 and 17—17.

In order to provide the cavity 11 with a smooth top surface flush with the side edges of the holder 10, a plate 18 is introduced and is provided with a plurality of strips 19 which are of the form and size of the slots required in the holder 10 for receiving the replaceable cutting blades, which will be later described. These strips 19 extend outwardly on one face of the plate 18 a lesser distance than the depth of the cavity 11, so that when the plate 18 is placed in face to face position with the holder 10, the strips 19 will extend into the cavity 11 without touching the surface 12 or the side edges 13 of the cavity.

After the holder 10 and plate 18 have been properly positioned, they are clamped together by means of a C-clamp 20 or other suitable fastening means and placed in a position of approximately 45° with the relieved portion 15 of the holder located at the top, and when in this position, the strips 19 are disposed vertically in the cavity 11.

In order to properly position the holder 10 and plate 18 with respect to the strips 19, a ledge 21 is provided on the plate 18 against which the holder 10 is brought to rest prior to clamping or securing the same in position. At this time, a molten mass of metal A is introduced and poured through the relieved portion 15 of the holder and plate 18 into the cavity 11 and around the strips 19 to fill the cavity and to fully surround the strips with the adjacent face 18a of the plate 18 serving as a smooth surface providing a finish to the metal A when it has cooled.

After the metal A is sufficiently cooled, the assembly may be separated by removing the holder 10 from the plate 18, which removes the strips 19 from the metal A leaving a plurality of elongated slots 22.

To accommodate for various kinds of cutting blades 23, it is sometimes desired to stagger the slots 22 with respect to their longitudinal positions, this being provided for in the positioning of the strips 19 on the plate 18 prior to the clamping of the same to the holder 10.

In order to provide means for securing the cutting blades 23 into the molded slots 22, the strips 19 are each provided with spaced apart openings 24—25, which are aligned when the strips are secured to the plate 18, and these openings 24—25 are also aligned with the openings 16—16 and 17—17, respectively, of the holder. Prior to pouring the metal A into the cavity 11, a rod 26 is inserted through openings 16—16 of the holder and openings 24 of the strips 19 and a rod 27 is inserted through openings 17—17 of the holder and openings 25 of the strips, so that the metal A poured into the cavity 11 will surround the rods 26 and 27 and provide transverse openings 28 and 29, respectively, in the metal A, and which openings are aligned with openings 16—16 and 17—17 of the holder 10.

The metal A poured into the cavity 11 of the holder 10 will form bases 30 (Fig. 3) of the proper depth and of uniform alignment with respect to the series of cutting blades 23 to be inserted within the slots 22 regardless of the irregularity of the surface 12 of the cavity. The metal A also forms spacer means between the edges 13 of the cavity 11 to properly position the cutting blades 23 and to prevent end thrust movement of the cutting blades while in the holder.

When the cutting blades 23 are positioned in the slots 22, retaining members 31—32 are then inserted through the openings 16—28 and 17—29 of the holder 10 and through openings 23a—23a in the cutting blades to retain them in rigid position against their bases 30 and snugly held against sidewise movement by reason of the close fitting of the cutting blades in the slots 22.

In the manufacture of cutting blades of the type employed for meat tendering machines, it is desirous to have a discontinuous cutting edge and with the blades arranged in staggered relation so as to thoroughly and completely sever the tendons and ligaments in the meat without completely severing the meat into smaller pieces.

When it is desired to remove any or all of the cutting blades 23 from the holder 10, the retaining members 31—32 are withdrawn, which renders the cutting blades free to be removed, and due to their snug fit in the slots 22, provision is made for easily removing the cutting blades.

The cutting blade is provided at each end thereof adjacent the surface of the metal A with a notched-out portion 33 into which the end of

a screw driver or other instrument may be inserted to force the cutting blade 23 out of the slot 22 for removal.

As the cutting blades are usually employed in connection with a cutting board, the blades may be positioned into the slots 22 a sufficient distance to retain them in position, and by then pressing the holder 10 against the cutting board (not shown), the cutting blades will be forced into their respective slots 22 to the limit of their movements, and at which time, the retaining members 31 and 32 may be inserted to securely retain the cutting blades on the holder.

I claim:

1. The method of making a holder adapted to receive a plurality of individually removable knives by molding a base with slots therein in a frame which comprises providing said frame with a bottom and inwardly sloping side members to form a recess undercut along said side members, positioning said frame upon a cooperating mold member having a plurality of projecting strips of the shape of said knives, centering said frame upon said mold member to predetermine the position of said strips within said recess in said frame, holding said frame and said mold together, filling said recess with a molten material through an opening in one of said sides of said frame, separating said frame and said mold member when said molten material solidifies whereby said solidified material forms said base with said slots therein, and thereafter utilizing said frame as said holder with said base locked therein along said undercut sides.

2. The method of making a holder adapted to receive a plurality of individually removable knives by molding a base with slots therein in a frame which comprises providing said frame with a bottom and inwardly sloping side members to form a recess undercut along said side members, positioning said frame upon a cooperating mold member having a plurality of projecting strips of the shape of said knives, centering said frame upon said mold member to predetermine the position of said strips within said recess in said frame, holding said frame and said mold together, filling said recess with a molten material, separating said frame and said mold member when said molten material solidifies whereby said solidified material forms said base with said slots therein, and thereafter utilizing said frame as said holder with said base locked therein along said undercut sides.

3. The method of making a holder adapted to receive a plurality of individually removable knives by molding a base with slots therein in a frame which comprises providing said frame with a bottom and side members to form a recess, positioning said frame upon a cooperating mold member having a plurality of projecting strips of the shape of said knives, centering said frame upon said mold member to predetermine the position of said strips within said recess in said frame, holding said frame and said mold member together, filling said recess with a molten material, separating said frame and said mold member when said molten material solidifies whereby said solidified material forms said base with said slots therein, and thereafter utilizing said frame as a holder with said base locked therein.

MILES M. ABBOTT.
